UNITED STATES PATENT OFFICE.

OSCAR R. LOOKER, OF DETROIT, MICHIGAN.

DESIGN FOR A NECKTIE-FORM.

SPECIFICATION forming part of Design No. 33,491, dated October 30, 1900.

Application filed October 6, 1900. Serial No. 32,309. Term of patent 7 years.

To all whom it may concern:

Be it known that I, OSCAR R. LOOKER, a citizen of the United States, residing at Detroit, in the county of Wayne, State of Michigan, have invented and produced a new and original Design for a Necktie-Form, reference being had to the accompanying drawings, and to the figures of reference marked thereon, which form a part of this specification.

This invention relates to a design for a necktie-form, as shown in the accompanying drawings, in which—

Figure 1 is a perspective view of my new design. Fig. 2 is a plan view thereof. Fig. 15 3 is a sectional view on line 3 3 of Fig. 1.

The leading feature of the design consists in the body portion having an upwardly-projecting tapering end with a notch therein and having laterally-projecting wings extending 20 on opposite sides at an angle to the plane of the body.

Referring to the characters of reference, 1 designates the body portion, and 2 the upwardly-projecting top part thereof, having the central notch 3. The flaring lateral wings 25 are designated at 4, the lower edges 5 of said wings depending slightly below the bottom of the body portion 6 and the whole presenting a harmonious and ornate figure.

Having thus fully set forth my invention, 30 what I claim as new, and desire to secure by Letters Patent, is—

The design for a necktie-form substantially as herein shown and described.

In testimony whereof I sign this specification in the presence of two witnesses.

OSCAR R. LOOKER.
